CLAIM

The ornamental design for an automobile body, as shown and described.

DESCRIPTION

FIG. 1 is a front and right side perspective view of an automobile body showing our new design;

FIG. 2 is a rear and left side perspective view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a rear elevational view thereof; and

FIG. 8 is a fragmentary perspective view of the right side of an automobile body showing a second embodiment of our design, it being understood that the sole difference resides in the omission of windows in the rear quarter panel and the sliding side door.

The broken lines in the drawings are for illustrative purposes only.

FIG. 1.

FIG. 2.

FIG. 3.

FIG. 1. 2.

FIG. 1. 7.
